EDWIN J. AHRENS, OF CINCINNATI, OHIO, ASSIGNOR, BY MESNE ASSIGNMENTS, TO
RUEBEN ELI OTTENHEIMER, OF BALTIMORE, MARYLAND

REFRIGERATING APPARATUS

Application filed August 24, 1929. Serial No. 388,138.

This invention relates to improvements in refrigerating apparatus. One of its objects is to provide improved means to render the contents of refrigerated show-cases clearly visible from the exterior and prevent deposits of dust or moisture upon the transparent panels thereof. Another object is to provide for one or more chambers in communication with the spaces between the double transparent walled sections of the show-case containing a dehydrating substance and accessible to remove and replace the dehydrating substance from time to time. Another object is to provide in combination with double transparent walled sections of a refrigerated show-case a chamber in communication with a single space between said double walls so arranged as to cause an automatic circulation of air from said chamber to and from said space and a dehydrating substance located in said chamber. Another object is to provide with plural transparent walled sections of a refrigerated show-case a chamber in communication with a plurality of spaces between said plural walls so arranged as to cause an automatic circulation from one of said spaces through said chamber into another of said spaces, a dehydrating substance in said chamber in the path of said circulation, and preferably means to remove and replace said dehydrating substance if and when required. My invention also comprises certain details of form and arrangement, and combination of components, all of which will be fully set forth in the description of the accompanying drawing, in which:

Fig. 1 is a central vertical section through a refrigerated show-case embodying my improvements.

Fig. 2 is a sectional detail taken on line 2—2 of Fig. 1.

Fig. 3 is a perspective view of a detachable container for a dehydrating substance.

Fig. 4 is a view similar to Fig. 1, illustrating a modification.

Fig. 5 is a front view of a portion of the apparatus shown in Fig. 4.

It is desirable to employ refrigerated show-cases for the display of meats, candies, and other goods requiring refrigeration, and in

order to prevent excessive refrigeration losses, it is requisite to employ two or more glass panels with interposed sealed air spaces to act as insulating spaces. In practice these sealed air spaces are not entirely free from moisture, and are not entirely free from dust, and upon the application of refrigerated air to the inside transparent panel and relatively much warmer air to the outside panel, a condensation of moisture or combined moisture and dust is liable to occur locally so as to materially obscure vision through the transparent wall sections of the refrigerated show-case, and to also materially detract from the appearance of the show-case. Where a dehydrating substance is sealed into the spaces between the transparent wall sections, if a leakage of moisture occurs, an abnormal accumulation of moisture in the leaking space is liable to occur, necessitating removal of the panels and repairs.

In order to obviate these various difficulties, I provide either with each space between transparent panels, or with each group of spaces, a chamber having communication through one or more conduits with said space, or with the respective spaces of a group, so arranged as to cause a natural or automatic draft under influence of the material differences in temperature from said chamber to and from said space, or from one of the spaces of a group through said chamber and into another of said spaces.

The accompanying drawing illustrates one embodiment of my invention, in which 15 represents the framework of a show-case. The front of the show-case is illustrated as comprising three transparent panels, 16, 17, and 18, set in the framework 15 and spaced apart by means of parting strip 19, and 20, to form arm chambers 21 and 22, which are sealed off from communication with the exterior or interior of the casing by varnishing the joints or similar sealing means. A transparent panel 23 is mounted in the top of the casing 15. A door 24 is hinged at 25 and latched at 26, and provided with two glass panels 27 and 28, and an interposed air space 29. If desired two or more panels with interposed air spaces may be employed in place of the single

panel 23 at the top of the casing. The ends of the casing are preferably provided with two or more transparent panels with interposed air spaces similar to those shown at the 5 front of the casing. A chamber 30 is thus provided within the casing to hold and display the goods to be vended. The door 24 gives access to the chamber 30 to introduce and remove the goods. A refrigerating coil 10 31, through which cold brine or gas is circulated, serves to keep the chamber 30 and its contents refrigerated to any desired extent. The air spaces between the transparent panels 15 act as heat insulating members, and reduce the refrigerating losses, while at the same time enabling the goods within the chamber 30 to be observed from the exterior of the casing.

The lower sections of the parting strips 19 20 are provided each preferably with two or more perforations 32, and the parting strips 20, preferably with two or more perforations 33. Beneath the parting strips 19 and 20 is placed a fine mesh wire screen 34 extending 25 beneath the perforations 32 and 33. Located in the wall of the casing 15 is a chamber 37 closed by means of a detachable lid or plate 35, located either in the front or rear face of the wall of the casing 15. A tray or 30 container 36 is located detachably in the chamber 37 and serves to hold a dehydrating substance, such as calcium chloride. Interposed between the plate 35 and the adjacent wall of the container 36 is a body 39 of heat 35 insulating material, sheet cork, for instance. As shown in Figs. 1 and 2, the plate 35 is held in place by means of a series of screws 38. Ports 40 lead downwardly from the perforations 32 and screen 34 to the chamber 37. 40 Ports 41 lead downwardly from the perforations 33 and screen 34 to the chamber 37.

Since the temperature to which the panel 18 is exposed is much lower than the temperature to which the panel 16 is exposed, the air 45 in the space 22 is cooled below the temperature in the space 21, and the air in space 21 is lower than the temperature of the air outside of the panel 16. Also the application of low temperatures from the chamber 30 to 50 the panel 18 causes cool air currents to flow downwardly along the face of the panel 18 within the space 22, and counter currents to flow upwardly within space 22 along the face of panel 17 and other places wherever the air 55 is warmer than at the face of the panel 18. In a similar manner air currents are set up within the space 21 downwardly where low temperatures exist, along the face of panel 17, and upwardly along the face of panel 16, for instance. Similar air currents are set up 60 within the air space 29 and at the ends of the casing.

It is of minor importance to keep the space 29 free from moisture as it is not directly in the view of customers, and is not used by

customers to view the contents of chamber 30. The transparent panels and air spaces at the ends of the show-case are preferably but not necessarily dehydrated as described for the front panels and air spaces, as the front panels are chiefly in view and chiefly employed by customers to view the contents of chamber 30.

The air within the air spaces such as 21 and 22 contains a certain amount of moisture, and the moisture and dust tend under the influence of refrigeration within the chamber 30 to deposit upon the faces of the panels such as 16, 17, and 18, and to reduce their transparency, and the ability of customers 70 to see the goods within the chamber 30 through said panels and to materially detract from the appearance of the show-case.

By connecting the spaces such as 21 and 22 by means of ports such as 32 and 33 with the chamber 37, there are formed connecting channels which serve both to connect the chamber 37 with the space 21 so as to provide for a circulation of air from space 21 to and from the chamber 37, and also to provide for an air circulation from space 22, where a plurality of air spaces are employed to and from the chamber 37, and also where a plurality of air spaces are employed to provide an air circulation through the chamber 37 to and from air space 21 to air space 22. The container 36 and its contents comprising a dehydrating substance being located in chamber 37 in the path of air currents flowing through chamber 37 to and from the air 90 spaces, enables and insures the continuous removal of any moisture from the air sealed within the air space or spaces and communicating chamber 37, thereby causing the dust to settle out by gravity and the panels to 100 continue in a clean transparent condition as when first assembled. At intervals of six months to a year, or more often in humid localities, the lid 35 and insulation 39 may be removed and the container 36 removed and 105 cleaned and its dehydrating contents renewed, after which the container 36 is replaced and the chamber 37 sealed by replacing the insulation 39 and the lid 35. In the modification Figs. 4 and 5 a lid 52 corresponding to the lid 35 of Fig. 1 is detachably held in place by means of a latch bar 53 hinged at 54 and latched to the casing 15 at 55. A hand lever 56 is pivotally attached to the middle portion of the bar 53 and provided 110 with an eccentric 57 to bear upon and hold the plate 52 in place, and at the same time provide a means adapted to more quickly detach and replace the lid 52 than the screws 115 shown in Fig. 1.

It is impossible without excessive expense to entirely or completely seal air within the spaces so as to prevent introduction of moisture therein from time to time, and the means herein shown and described provides for an 120 125 130

automatic or natural circulation of air from the air spaces into contact with the dehydrating substance and return, and provides for keeping the panels clean and transparent over long periods of time, provides for keeping the show-case in attractive condition and appearance, and provides for renewal of the dehydrating material all at a minimum of attention and expense.

10 The apparatus herein shown and described is capable of considerable modification within the scope of the claims without departing from the spirit of my invention.

What I claim is:

15 1. In a refrigerated show-case a casing enclosing a refrigerated chamber, a window to display the contents of said refrigerated chamber comprising a plurality of transparent panels defining an interposed substantially sealed air space, a chamber containing a dehydrating substance located in the wall of said casing having a port leading therefrom to said substantially sealed air spaces and an entrance from one face of the casing 20 wall, a lid detachably attached to the face of said casing to close the entrance to said dehydrating chamber and readily releasable lever mechanism operable to hold said lid detachably in place, the port leading from said 25 air space to said dehydrating chamber being of sufficient capacity to maintain a circulation of air to and fro from said air space to said dehydrating chamber.

30 2. In a refrigerating apparatus, a window frame, a plurality of spaced panes mounted in said frame to provide space between said panes, strips spacing said panels from each other, a dehydrating chamber located in the wall of said casing, ports communicating 35 with the spaces between said panels and the dehydrating chamber, a removable tray in said dehydrating chamber, a moisture absorbing medium located within said tray, said dehydrating chamber having a door communicating therewith, means comprising a layer 40 of heat insulated material located between said door and said tray for preventing the entrance of heated air to the said chamber and a latch on said door for holding the same 45 in readily releasable position said latch having means for tightly holding said door against said casing.

50 3. In a refrigerating apparatus, a window frame, a plurality of spaced panes mounted in said frame to provide space between said panes, strips spacing said panels from each other, a dehydrating chamber located in the wall of said casing, ports communicating 55 with the spaces between said panels and the dehydrating chamber, a removable tray in said dehydrating chamber, a moisture absorbing medium located within said tray, said dehydrating chamber having a door communicating therewith, means comprising a layer 60 of heat insulated material located between 65

said door and said tray for preventing the entrance of heated air to the said chamber and a latch on said door for holding the same in readily releasable position said latch having means for tightly holding said door 70 against said casing including a cam portion movable against said door.

In testimony whereof I have affixed my signature.

EDWIN J. AHRENS. 75
